ROBERT LEE KOHLER, OF LOS ANGELES, CALIFORNIA, ASSIGNOR OF ONE-TWENTIETH
TO MILLER S. KIELSGARD, OF FAIRFAX, VIRGINIA

NONCURLING ELASTIC LACE FOR WEARING APPAREL

Application filed November 27, 1928. Serial No. 322,201.

The invention relates to improvements in elastic laces for wearing apparel, such as, riding breeches, leggings and footwear, and the objects of the improvement are, first, to prevent curling of the laces when in use; second, to provide a firmer center than edge in laces, thus preventing their coming undone easily; and, third, to provide greater strength although retaining their elasticity.

The invention is illustrated in the accompanying drawing, in which Figure 1 is a vertical section of the lace; Figure 2 a cross-section of the oval lace, and Figure 3 a cross-section of a flat lace which is interwoven so as to provide a slightly raised center upon one face.

Figure 1 shows a middle strand of suitable elastic material 1, separately covered by an extensible envelope woven or otherwise suitably secured upon it by threads 2. Upon opposite sides of the middle elastic strand made up of 1 and 2, two smaller strands of elastic material 3 are placed. The separately covered and larger elastic strand 1, together with the two smaller elastic strands 3 are then covered by a less closely woven or otherwise united extensible envelope of suitable material 4.

Figure 3 shows the same arrangement except that the outer envelope is interwoven with the inner envelope so as to provide two covers upon the middle strand. The elements of the device shown in Figure 3 are similar to the elements shown in Figure 2, except that a flat lace is shown in Figure 3 instead of an oval lace, and the numerals 1', 2', 3' and 4' are used to indicate the respective elements to avoid confusion.

I am aware that prior to my invention elastic laces have been made and I claim but three improvements.

I claim:

1. A lace comprising a plurality of strands of elastic material, one of said strands being separately covered with an envelope the threads of which are closely united, and a second envelope covering all of said strands and having its threads less closely united than said first mentioned envelope.

2. A lace comprising a plurality of strands

of elastic material, the central strand being larger than the remaining strands and being separately covered with an envelope having its threads closely united, all of said strands being covered by a second envelope to form a unitary structure, said second envelope having its threads less closely united than said first mentioned envelope.

3. A lace comprising a central strand of elastic material, an envelope formed of threaded closely united material and covering said central strand, a plurality of additional strands of elastic material of less thickness than said central strand arranged adjacent said envelope in parallel relation with said central strand, and a second envelope surrounding all of said strands and being formed of threaded material less closely united than said first mentioned envelope.

4. A lace comprising a plurality of strands of elastic material, the central strand being larger than the remaining strands and being separately covered with a closely woven envelope, and a second envelope covering all of said strands and being less closely woven than said first mentioned envelope, portions of said envelopes being interwoven with each other on opposite sides of said central strand.

ROBERT LEE KOHLER.
